REMOTE CONTROL AND INDICATING
SYSTEMJoseph T. McNaney, Baltimore, Md., assignor to
Bendix Aviation Corporation, Towson, Md., a
corporation of Delaware

Application August 22, 1946, Serial No. 692,393

12 Claims. (Cl. 318—18)

1

This invention relates to remote control and indicating systems, more particularly to systems which provide control by electrical coupling to actuate a remotely located mechanism to a desired position or station, and provide repeat-back means for indicating at the control station the position of the actuated mechanism.

A variety of weaknesses are inherent in previous electrically energized remote control systems. One weakness is the requirement of added component units such as amplifiers for "servo" systems, or power packs for energy conversion in case more than one form of operating current is required. Another weakness is the inability of some systems to function rapidly and, at the same time, be adequately responsive to the minute adjustments required in certain applications. In some applications of remote control the remote drive does not accurately follow the local directive movement. Similarly, the lag of the remote drive often resolves to "hunting" at the end of an adjustment operation.

An object of this invention is to provide a system for local control of a remote position or station selecting mechanism, and feed-back indication of that position, which functions entirely from a direct current voltage source.

Another object of this invention is to provide such a system which develops high torque.

Still another object of this invention is to provide such a system in which the remote drive follows the local control with positive synchronism at any speed within the limits of normal operation.

A further object of this invention is to provide such a system in which the speed of the remote drive can be readily controlled to provide maximum position coverage with a minimum of time.

Another object of this invention is to provide such a system in which the desired station or position is selected and retained with positive stability.

Still another object of this invention is to provide such a system which requires a minimum of installation space at both the remote and local positions, and which requires no separate units for its operation.

In accomplishing these objects step-by-step switches in the form of commutators are used in conjunction with reversible direct current motors equipped with electromagnetic clutches and fast-stopping brakes. A compound gear ratio provides adequately small steps for posi-

tion adjustment as well as extra high torque at the load.

Other objects and advantages of this invention will become apparent from a consideration of the following specification when taken in conjunction with the accompanying drawing in the single figure of which is shown a schematic diagram of a remote control and indicating system embodying the invention.

10 The objects and advantages of the invention are realized by a system employing a motor to drive the remotely located mechanism, the motor being energized in a step-by-step fashion through a pair of commutators, one located at the control station and crank-driven, and the other located in the remote station and driven by the motor through a magnetic clutch and brake which provides fast stopping of the remote commutator upon the interruption of the motor energizing circuit. Suitable gearing is provided between the crank and the motor and their respective driven devices to provide desired step values and torque at the driven mechanism. A sense switch is incorporated in the crank drive.

25 A centrifugal switch carried by the remote commutator operates upon rotation of that commutator in excess of a certain speed to provide continuous excitation of the motor for high speed actuation of the remote mechanism. Repeat-back indication of the position of the actuated mechanism is provided by means including a motor positioned at the control station and driving a dial pointer, the motor being energized in a step-by-step fashion through two commutators,

30 one driven by the remote mechanism driving motor and the other driven by the repeat-back motor through a magnetic clutch and brake. Gear drive ratios are selected to prevent lag between the commutators and a warning means is provided to indicate any misalignment which might occur between the commutators due to faulty brush contacts.

35 Referring now more particularly to the drawing, which is divided into two portions by the dashed line A—B, the portions representing a control station and a remote station, as indicated, there is shown a crank 10 located in the control station and mechanically connected to a resilient member 31 which acts as the switch arm of a sense switch 12 and is mounted for rotation with a shaft 14. Likewise mounted for rotation with shaft 14 is a member 38 carrying contacts 42 and 46, and also forming a part of the sense switch 12. Associated with the shaft 14 are three slip rings 28, 25 and 27, contact 42

being connected to slip ring 27 and contact 46 being connected to slip ring 25. Member 31 is connected to slip ring 23. Movement of the crank 10 in either direction will flex the member 31 until it establishes contact with either contact 42 or contact 46, whereupon further rotation of the crank will, by the application of torque through the members 31 and 38, cause rotation of shaft 14.

A D. C. motor 18, located in the remote station, is energized through a lead 11 from a source of direct current and drives a commutator 22 and an actuated mechanism 28 through a magnetic clutch and brake 20.

The clutch and the brake 20 may be of the type disclosed in U. S. Patent 2,267,114 for Electro-magnetic clutch, issued December 23, 1941, to Lear et al. The clutch consists of a clutch plate 35 and a clutch plate 37, the latter being normally spring pressed into braking engagement with the braking surface 39 carried by a rigid support. Upon the passage of current through coil 15 of lead 11, during the energization of the motor 18, the two clutch plates are urged into clutching relationship, the plate 37 alone being movable. Upon interruption of current flow through the lead 11, the plate 37 is immediately urged into braking contact with braking surface 39, stopping the shaft-carrying commutator 22 and actuated mechanism 28 almost instantly, the motor 18 continuing to coast to a stop. The energizing circuit of motor 18 includes the exciting coil 17, the terminals of which are connected respectively to slip rings 25 and 27 of the sense switch 12. The sense switch 12, by virtue of the resiliency of member 31, remains open in the absence of any actuation of the crank 10. However, movement of the crank 10 in either direction, causing member 31 to make contact with one of the contacts 42 or 46, thus determines the direction of current flow through the exciting coil 17 and consequently determines the direction of rotation of motor 18.

The mechanical connection 14 between the switch 12 and the commutator 16 may include gearing designed to give any desired ratio of rotational movement of the commutator 16 with respect to the crank 10. Likewise the commutator 16 may be provided with any desired number of segments, being shown here as having eight segments 41. Two slip rings 45 and 47 are provided, the commutator segments 41 being connected to the slip rings in alternation. Electrical connections are established between the commutator 16 and the commutator 22 by two leads 51 and 52 terminating at the commutator 16 and brushes 49 and 50 co-acting respectively with the slip rings 45 and 47. The commutator 22 is provided with four segments connected in alternation to two slip rings 55 and 56, the leads 51 and 52 terminating in brushes 53 and 54 co-acting with the slip rings. A lead 13 connects the commutator 22 with the source of direct current, terminating at the commutator 22 in a brush 58.

The commutator 22 is provided with a centrifugal switch 24, which upon rotation of the commutator 22 in excess of a predetermined speed, closes, cross-connecting the leads 51 and 52 and thus establishing continuous excitation of the motor 18 when the crank 10 is turned in excess of a certain speed.

The mechanical connection between the commutator 22 and the actuated mechanism 28 may be provided with gearing designed to give the de-

sired ratio of commutator movement to movement of the actuated mechanism. This gearing, together with that between the crank-driven switch 12 and commutator 16, may be so designed, and may be varied, as to give any desired number of motor exciting impulses per unit of angular or rotational movement of the actuated mechanism.

For the purpose of providing repeat-back information as to the position of the actuated mechanism, a commutator 30 driven by the motor 18 is provided in the remote station. The commutator 30 is provided with four segments 60, 61, 62 and 63 connected respectively to four slip rings 64, 65, 66 and 67. The commutator 30 is electrically connected to a commutator 40 located in the control station, by four leads 81, 82, 83 and 84. The commutator 40 is provided with four segments 68, 69, 70 and 71 corresponding to the segments in commutator 30 and connected to separate slip rings. The leads 81, 82, 83 and 84 co-act with the slip rings of commutators 30 and 40 in a manner to maintain connection between respective corresponding segments of the two commutators.

The commutator 40 is mechanically driven by a motor 34, which is similar to the motor 18, through an electro-magnetic clutch and brake 36 which is of the same type as the clutch and brake 20. The motor 34 also mechanically drives a dial pointer 89 co-acting with a dial 88, for the indication of the position of the actuated mechanism. Positioned about the periphery of the commutator 40, in contacting relation with three adjacent segments thereof are brushes 72, 73 and 74. Brushes 72 and 74 are connected by leads 90 and 91 to the terminals of exciting coil 80 of motor 34. Four resistors 75, 76, 77 and 78, of equal values, are serially connected between leads 90 and 91. The junction point of resistors 76 and 77 is connected to the brush 73. Connected between the junction point of resistors 75 and 76 and the junction point of resistors 77 and 78 is a solenoid 79, comprising a pair of coils 93 and 94, a corresponding terminal of each being connected to the above mentioned junction points and the remaining terminals being connected together and to a lead 87. A flag 48 actuated by solenoid 79 is so mounted that in the absence of such actuation it lies in invisible relationship to an opening 93 formed in a panel 92 visible to the operator. Energization of the motor 34 is completed through the lead 87 and a lead 86 terminating in a brush 85, in contacting relation with commutator 30, which leads may be connected through the same D. C. voltage source as utilized for the motor 18.

Proceeding now to the operation of the system, an operator desiring to cause rotation of the actuated mechanism turns the crank 10 in the direction in which he desires such rotation to take place. Supposing such movement to be desired in the clockwise direction, displacement of the crank in this direction causes the member 31 to make contact with contact 46, thus completing the circuit through the coil 17 in such a direction as to cause clockwise rotation of the motor 18. The energization of the motor 18 actuates the electro-magnetic clutch and brake 20 with consequent rotation of the commutator 22 and the actuated mechanism 28. Rotation of the crank 10 causes corresponding or related rotation of the commutator 16 in the same direction, the electrical connections between the commutators 16 and 22 regulating the energization of the motor 18, in a manner determined by the

relative number of segments of the commutators 16 and 22 and the drive ratio between the motor 18 and the commutator 22, to cause the speed of rotation of the motor 18 to correspond to the speed of the commutator 16 and to vary therewith. On the rotation of the crank 10 at a speed above a predetermined limit the centrifugal switch 24 is closed, thus providing continuous excitation of the motor 18 to its characteristic speed under such excitation. After the motor 18 has attained its characteristic speed it will continue at that speed if the rotation of the crank is reduced below the predetermined speed referred to above, or even stopped, so long as the member 31 is maintained in contact with contact 46. In order to stop the rotation of the motor 18 and the actuated mechanism, it is only necessary to open the switch 12 either by removing the hand from crank 10 or by moving the crank a few degrees in the opposite direction. This will interrupt the energization of the motor and cause the clutch portion of the electro-magnetic clutch and brake 20 to be disengaged, allowing the braking portions to come into contact and immediately stop the rotation of the commutator 22 and the actuating mechanism 28.

As has been stated, the gear ratio between the crank-driven switch 12 and the commutator 16 and that between the commutator 22 and the actuated mechanisms 28 may be selected together with the number of segments in the commutator 16 to give the desired number of steps of motor energization for each unit of rotation of the actuated mechanism. By way of example, with a gear ratio of 1 to 15 between the switch 12 and the commutator 16 and a gear ratio of 3600 to 1 between the commutator 22 and the actuated mechanism 28, 60 turns of the crank 10 would produce 7200 steps of motor excitation which would correspond to 180 degrees of rotation of the actuated mechanism 28, which might, for example, be a condenser.

When the motor 18, and therefore the commutator 30, are at rest, the commutator 40 will be so positioned that the segment lying under neutral brush 73 is connected to the segment of commutator 30 which lies under the brush 85. When rotation of motor 18 is initiated in the clockwise or counterclockwise direction, segment 62 or 60, respectively, of the commutator 30 will be brought under the brush 85. If the segment 62 is brought under the brush 85 the positive lead 86 will be connected to the segment 69 of the commutator 40 and the motor 34 will be energized in a manner to bring the segment 69 under the neutral brush 73 whereupon the commutator 40 will be instantly stopped by the operation of the electro-magnetic clutch and brake 36. If the segment 60 of commutator 30 is brought under the brush 85, the segment 71 of the commutator 40 will be connected to the positive side of the line and the motor will be driven in the opposite direction to bring segment 71 under neutral brush 73, whereupon the motor will again be stopped.

It is possible to select a gear ratio between the motor 34 and the commutator 40 which will not permit the commutator 40 to lag behind the commutator 30. However, in the event the commutator 40 gets out of step with the commutator 30, due to faulty brush contacts or other reasons, the segment of the commutator 30 brought under the brush 85 will be the one which is not connected to any of the brushes of commutator 40, and, as a result, solenoid 79 will be de-energized,

thus permitting the flag 48 to fall into visual position within the opening 93 of the panel 92 and warning the operator that such misalignment has occurred.

5 Gear ratios may be selected as desired between commutators 22 and 30, and between commutator 40 and pointer 89, to give the desired amount of pointer movement per unit of rotation of the actuated mechanism 28. Suppose, for example, 10 that the gear ratios mentioned above are in use and it were desired to have the pointer 89 moved in stepwise fashion one step for each half degree of rotation of the actuating mechanism 28. Further suppose that the scale of the dial 88 be 15 desired to be spread over an arc of 300 degrees to represent 180 degrees of rotation in the actuated mechanism 28. In that case, a gear ratio of 12 to 1 between the commutator 22 and the commutator 30 could be used, with a ratio of 180 20 to 1 between the commutator 40 and the dial pointer 89. When desired, the speed of the motor 34 can be stepped up above that of the commutator 40 such, for example, as by ratio of 10 to 1. Other gear ratios may be selected to suit 25 the needs of the user, the system being capable of extreme flexibility in this respect.

While the disclosure has been restricted to that form of the invention which is now preferred, the invention is not to be considered as restricted thereto, since many changes in form and arrangement falling within the scope of the invention as defined by the appended claims, will occur to those skilled in the art.

What is claimed is:

- 35 1. A system for positioning a remotely located mechanism from a control station which comprises; a motor driving said mechanism, a circuit for the energization of said motor, said circuit comprising a first commutator located in said control station, means in said control station for driving said commutator, said means controlling the sense of application of exciting energy to said motor through said energizing circuit in accordance with the direction of rotation of said commutator, a second commutator driven by said motor and forming part of said energizing circuit, said first and second commutators being electrically connected, whereby upon the operation of said commutator driving means said motor 40 will be energized by sequential impulses to a speed and direction of rotation which are functions of the speed and direction of the rotation of said driving means, means operable by centrifugal force generated upon the rotation of said driving 45 means in excess of a predetermined speed to provide continuous excitation of said motor, and means operable upon the interruption of said energizing circuit to disconnect said motor from said second commutator and said mechanism and to stop the rotation of said mechanism.
- 50 2. A system for positioning a remotely located mechanism from a control station which comprises; a motor driving said mechanism, a circuit for the energization of said motor, said circuit comprising a first commutator located in said control station, means in said control station for driving said commutator, said means controlling the sense of the application of exciting energy to said motor through said energizing circuit in accordance with the direction of rotation of said commutator, a second commutator driven by said motor and forming part of said energizing circuit, said first and second commutators being electrically connected, whereby upon the operation of said commutator driving 55 means the motor will be energized by sequential impulses to a speed and direction of rotation which are functions of the speed and direction of the rotation of said driving means, means operable by centrifugal force generated upon the rotation of said driving means in excess of a predetermined speed to provide continuous excitation of said motor, and means operable upon the interruption of said energizing circuit to disconnect said motor from said second commutator and said mechanism and to stop the rotation of said mechanism.
- 60 3. A system for positioning a remotely located mechanism from a control station which comprises; a motor driving said mechanism, a circuit for the energization of said motor, said circuit comprising a first commutator located in said control station, means in said control station for driving said commutator, said means controlling the sense of the application of exciting energy to said motor through said energizing circuit in accordance with the direction of rotation of said commutator, a second commutator driven by said motor and forming part of said energizing circuit, said first and second commutators being electrically connected, whereby upon the operation of said commutator driving 65 means the motor will be energized by sequential impulses to a speed and direction of rotation which are functions of the speed and direction of the rotation of said driving means, means operable by centrifugal force generated upon the rotation of said driving means in excess of a predetermined speed to provide continuous excitation of said motor, and means operable upon the interruption of said energizing circuit to disconnect said motor from said second commutator and said mechanism and to stop the rotation of said mechanism.
- 70 4. A system for positioning a remotely located mechanism from a control station which comprises; a motor driving said mechanism, a circuit for the energization of said motor, said circuit comprising a first commutator located in said control station, means in said control station for driving said commutator, said means controlling the sense of the application of exciting energy to said motor through said energizing circuit in accordance with the direction of rotation of said commutator, a second commutator driven by said motor and forming part of said energizing circuit, said first and second commutators being electrically connected, whereby upon the operation of said commutator driving 75 means the motor will be energized by sequential impulses to a speed and direction of rotation which are functions of the speed and direction of the rotation of said driving means, means operable by centrifugal force generated upon the rotation of said driving means in excess of a predetermined speed to provide continuous excitation of said motor, and means operable upon the interruption of said energizing circuit to disconnect said motor from said second commutator and said mechanism and to stop the rotation of said mechanism.

means said motor will be energized by sequential impulses to a speed and direction of rotation which are functions of the speed and direction of rotation of said driving means, and means operable by centrifugal force generated upon the rotation of said driving means in excess of a predetermined speed to provide continuous excitation of said motor.

3. A motor control system comprising an energizing circuit for said motor, said circuit comprising a pair of conductors providing alternative conductive paths, a control means rotatable in opposite directions and controlling the sense of the application of energy through said circuit to said motor in accordance with its direction of rotation, a pair of switching means, one of said switching means being driven by said control means and the other being driven by said motor, each of said switching means establishing contact sequentially between said conductors and the remainder of said circuit a plurality of times for each rotation of said control means, and means operable in response to rotation of said motor in excess of a predetermined speed to cross connect said conductors, thus providing said motor with continuous excitation.

4. A motor control system comprising an energizing circuit for said motor, said circuit comprising a pair of conductors providing alternative conductive paths, a control means rotatable in opposite directions and controlling the sense of the application of energy through said circuit to said motor in accordance with its direction of rotation, and a pair of switching means one of said switching means being driven by said control means and the other being driven by said motor, each of said switching means establishing contact sequentially between said conductors and the remainder of said circuit a plurality of times for each rotation of said control means.

5. A motor control system comprising an energizing circuit for said motor, said circuit comprising a pair of conductors providing alternative conductive paths, a control means, and a pair of commutators, each of said commutators having at least four segments, one of said commutators being driven by said control means and the other being driven by said motor, each of said switching means establishing contact sequentially between said conductors and the remainder of said circuit.

6. A motor control system comprising an energizing circuit for said motor, said circuit comprising a plurality of conductors providing alternative conductive paths, a single conductor forming part of said circuit, a switching means operative to establish contact sequentially between said conductors and said single conductor, a second switching means driven by said motor, an exciting coil for said motor forming a part of said energizing circuit, the direction of current flow through said coil determining the direction of rotation of said motor, said coil having a pair of terminals in conductive relation to said second switching means and a center tap conductively related to said motor, conductive means providing a branch of said circuit connected between said terminals, said branch having a terminal in conductive relation to said second switching means, said second switching means being operable to establish contact sequentially between the conductors of said plurality of conductors and each of the terminals of said coil and said branch, said terminals being so arranged that upon contact being established between one

5 of said plurality of conductors, said single conductor and one of the terminals of said coil, said second switching means will be so driven as to break the contact with said coil terminal and establish contact between said one of said plurality of conductors and the terminal of said branch, a warning device and means responsive to current flow through said branch by way of any of said terminals to maintain said warning device in a non-operating position.

7. A motor control system comprising an energizing circuit for said motor, a rotatable driving means, a rotatable switch forming a part of said circuit and being driven by said driving means, said switch normally being open and being closed in either of two directions by the operation of said driving means in accordance with the direction of rotation thereof, thereby controlling the sense of the application of exciting energy to said motor in accordance with the direction of rotation of said driving means, a commutator driven in accordance with the rotation of said driving means, a second commutator driven by said motor, each of said commutators comprising a plurality of conductive segments, means connecting the segments of each of said commutators in alternation into a plurality of conducting units, means conductively connecting the corresponding units of said commutators, said commutators forming part of said energizing circuit, and means operable by centrifugal force generated by rotation of said second commutator in excess of a predetermined speed to conductively connect all of the conductive units of said commutators.

8. In a motor control system comprising an energizing circuit for said motor, a rotatable driving means, a rotatable switch forming a part of said circuit and being driven by said driving means, said switch normally being open and being closed by said driving means in accordance with the direction of rotation thereof, said switch thereby controlling the sense of the application of exciting energy to said motor in accordance with the direction of rotation of said driving means, a commutator driven in accordance with the rotation of said driving means, a second commutator driven by said motor, each of said commutators comprising a plurality of conductive segments, means combining alternate segments of each of said commutators to form a plurality of conductive units and means conductively connecting the corresponding units of said commutators, said commutators forming part of said energizing circuit.

9. In a motor control system comprising an energizing circuit for said motor, a rotatable driving means, a commutator driven in accordance with the rotation of said driving means, a second commutator driven by said motor, each of said commutators comprising a plurality of conductive segments, means combining alternate segments of each of said commutators to form a plurality of conductive units and means conductively connecting the corresponding units of said commutators, said commutators forming part of said energizing circuit.

10. In a motor control system comprising an energizing circuit for said motor, said circuit comprising a plurality of conductors providing alternative conductive paths, a single conductor forming part of said circuit, a switching means operative to establish contact sequentially between said conductors and said single conductor, a second switching means driven by said motor, and an exciting coil for said motor forming a

part of said energizing circuit, the direction of current flow through said coil determining the direction of rotation of said motor, said coil having a pair of terminals in conductive relation to said second switching means and a center tap conductively related to said motor: the combination with said system of conductive means providing a branch of said circuit connected between said terminals, a third terminal connected to a central portion of said branch and in conductive relation to said second switching means, said branch including resistive means impeding the flow of current therethrough between said terminals, said switching means being operable to establish contact sequentially between the conductors of said plurality of conductors and each of said terminals, a warning device and means responsive to current flow through said branch by way of any of said terminals to maintain said warning device in a non-operating position.

11. The combination as set forth in claim 10, the last named means comprising inductive elements connected to respond to current flow in said branch.

12. The combination as set forth in claim 10, the last named means comprising a pair of solenoids connected in parallel between points on said branch intermediate respective pairs of said terminals and a point in said circuit, such that current flowing through said solenoids does not flow through said motor.

Certificate of Correction

Patent No. 2,496,485

February 7, 1950

JOSEPH T. McNANEY

It is hereby certified that error appears in the printed specification of the above numbered patent requiring correction as follows:

Column 7, lines 48 and 49, for the words "switching means" read *commutators*; and that the said Letters Patent should be read with this correction therein that the same may conform to the record of the case in the Patent Office.

Signed and sealed this 30th day of May, A. D. 1950.
